W. DAWSON.
Cigar Machine.

No. 14,763.

Patented Aug. 29, 1856.

UNITED STATES PATENT OFFICE.

WILLIAM DAWSON, OF HUNTINGTON, CONNECTICUT.

IMPROVEMENT IN CIGAR-MACHINES.

Specification forming part of Letters Patent No. 14,763, dated April 29, 1856.

To all whom it may concern:

Be it known that I, WILLIAM DAWSON, of Huntington, in the county of Fairfield, in the State of Connecticut, have invented a new and useful Machine for Making Cigars; and I do hereby declare that the following is a full, clear, and exact description of the construction and operation of the same, reference being had to the annexed drawings, making part of this specification, in which—

Figure 1 is a sectional longitudinal elevation. Fig. 2 is a transverse sectional view. Fig. 3 is one side view; Fig. 4, the other side view; Fig. 5, a plan; Fig. 6, a sectional view of the bed detached; and Fig. 7, a plan view of the bed detached, similar letters referring to similar parts in each.

A is the frame-work of the machine; B, shaft on which the wheel C and the gear-wheel F are placed; C, wheel, with a cam-slot, D, on its face, to work the cutter and presser, and also with a projecting plate, E, on the side of its periphery, to throw the clutch M in contact with the roller I; F, a gear-wheel on the end of the shaft B, gearing into the pinion H on the driving-shaft G; I, roller working loose on the shaft G, to which the strap J is fastened, for giving the forward motion to the bed.

M is a connecting-clutch, which works the roller I when thrown in contact with it by the projection E. It is disconnected by an arm on the bed striking and moving the lever N.

K is the movable bed, working in guides on the top of the frame; L, flexible apron fastened to and moving with the bed; O, the hopper for containing the supply of "filling." The filling is carried forward to the cutter and presser by the feeding-apron P, worked by the rollers Q Q Q Q. The apron is moved forward a distance proportioned to the size of cigar required by the pinions R R, the ratchet-wheel S, the catch T, the lever U, and the pin V on the back of the wheel F.

W is the cutter and presser, connected with the lever Y by the rod Z. It is moved downward by the cam-slot D, working the pin X on the lever Y, and moved upward by the counter-balance a when the pin is released from the slot.

b b are two forming-rollers for rolling up

the cigar. They are worked by pinions on their ends gearing into a rack on the inner side of the bed, as shown in Fig. 6. The outer roller works on the arms e e, and is moved away from the inner one when the cutter and presser W is moved downward, so as to allow the fillings to be pressed down onto the flexible apron L. It is brought back to its first position by a spring on the upward movement of the cutter and presser.

d d are the shaping-dies, to give form to the cigar. The inner die is permanently placed. The outer one is movable by being placed in a frame, and is moved by the strap e and lever f a sufficient distance from the other to permit the cigar to drop between them when completed.

g is a counter-balance to bring back the bed K by the strap h when the clutch M is disengaged.

i is an aperture in the flexible apron L, to allow the cigar to drop through.

The operation of the machine is as follows, viz.: The feeding-hopper O being supplied with fillings and the machine put in motion, the cutter and presser W is moved by the cam-slot in the wheel C, and cuts off the required amount of fillings and presses it between the rollers b b onto the flexible apron over the shaping-dies d d. The wheel C in its revolution brings the projection E into contact with the clutch M, and throws it in connection with the roller I. The strap J moves the bed K forward. The flexible apron L, attached to it, moves under the forming-rollers b b and over the shaping-dies d d, rolling the filling and giving it a proper compression. The "wrapper" is placed diagonally on the apron L, (after it has moved a short distance,) and is wrapped around the filling during the further movement of the bed, the shaping-dies giving to the cigar its proper form. When the bed K reaches nearly the end of its travel, the forward die d is moved by the strap e and lever f away from the back die, allowing the cigar to fall through the aperture i in the apron L into a box or other receptacle. When the bed K completes its forward movement, the lever N disconnects the clutch M from the roller I, and the counter-balance g brings the bed K back to its first position,

and the machine repeats the operation, as before. The cigars after leaving the machine are "headed" and cut to length by hand.

What I claim as my invention, and desire to secure by Letters Patent, is—

The combination of the forming-rollers *b b*, the flexible apron *L*, and the shaping-dies *d d*,

substantially as herein described, and for the purposes set forth.

WILLIAM DAWSON.
